Primary Examiner — Kimberly Barnes(74) *Attorney, Agent, or Firm* — Marshall, Gerstein & Borun LLP(57) **CLAIM**

The ornamental design for a tactile tile, as shown and described.

DESCRIPTION

FIG. 1 is a front view of a tactile tile of the new design; FIG. 2 is a bottom view of the tactile tile of FIG. 1; FIG. 3 is a right elevation view of the tactile tile of FIG. 1; FIG. 4 is a top view of the tactile tile of FIG. 1; FIG. 5 is a left elevation view of the tactile tile of FIG. 1; and,

FIG. 6 is a rear view of the tactile tile of FIG. 1. The unevenly broken lines in FIGS. 1 and 6 represent the boundary of the claimed design and form no part thereof. The evenly broken lines in FIGS. 2-5 of the drawings depict portions of the tactile tile that form no part of the claimed design.
